CLAIM

The ornamental design for a dihedral chair, as shown and described.

DESCRIPTION

FIG. 1 depicts a front side perspective view of a dihedral chair.

FIG. 2 depicts a front view of the dihedral chair.

FIG. 3 depicts a rear view of the dihedral chair.

FIG. 4 depicts a right side elevation view of the dihedral chair.

FIG. 5 depicts a left side elevation view of the dihedral chair.

FIG. 6 depicts a top plan view of the dihedral chair; and,

FIG. 7 depicts a bottom plan view of the dihedral chair. The shade lines in the Figures show contour and not surface ornamentation.
